CASTINGS COMPANY, OF CLEVELAND, OHIO, A CORPORATION OF OHIO.

DRAFT-RIGGING.

No. 914,089.

Specification of Letters Patent.

Patented March 3, 1908.

Application filed February 23, 1905. Serial No. 246,829.

To all whom it may concern:

Be it known that I, CLINTON A. TOWER, of Cleveland, Cuyahoga county, Ohio, have invented a new and useful Draft-Rigging, of which the following is a full, clear, and exact description, reference being had to the accompanying drawings, forming part of this specification, in which—

Figure 1 is a side elevation of my draft rigging partly in vertical section; Fig. 2 is a vertical cross-section on the line II—II of Fig. 1; and Figs. 3 and 4 are detail views.

In the drawings, 2 represents the draw-bar, 3 is a yoke which extends rearwardly therefrom, and 4, 5 are followers held respectively on opposite sides by means of the usual stops on the draft-timbers which may be applied in the way in which stops are ordinarily applied to the followers of draft-riggings. These followers are curved on their inner faces and bear against the curved faces of differential levers 6, 7, which have a rocking bearing 8 at their meeting faces and are forked or slotted so as to extend outwardly and preferably vertically downward beyond the line of the draw-bar and over the yoke 3 which passes through the forked or slotted portions. By the term differential levers, is meant levers in which the fulcrum or point of application of pressure, or both, alter their relative positions, so that the lengths of the respective arms of the levers are varied during the operation thereof. At the portions which extend outside the yoke, there is an interposed spring or combination of springs 9, preferably mounted on a rod or bolt 10 which extends through the projecting portions of the levers and is held preferably by a head 10' at one end and by a key or nut 10" at the other end. The outer faces of the levers 6 and 7 may be slotted or recessed so as to fit over the curved faces of the followers 4 and 5, and the meeting faces of the levers and followers, as well as the meeting surfaces of the levers are preferably correspondingly curved and corrugated or provided with teeth which will hold them from slipping out of position and will insure their regular and even movement. To connect the outer end of each lever with the spring-seats 11, I prefer to employ a conical thimble 12 which fits on the rod 10 and has a bearing on the spring-seat, thus giving the levers freedom of motion without binding on the bolt. Washers 55 of any desired number or thickness may

be interposed between the thimbles or levers and the head 10' and nut 10" respectively.

When the draw-bar is subjected to a buffing stress it will move the follower 5 rearwardly, and acting on the lever 7 will cause it to rock on the point 8 as a fulcrum, thus compressing the spring 9 and causing the lever 6 to rock to an equal extent in the opposite direction. As the followers move inwardly the points of contact between the respective followers 4, 5 and levers 6, 7 will shift gradually toward the inner ends of the levers. This increases the length of the long arms of the levers which bear upon the spring 9 and shortens the short arms which are between the contact points of the followers 4, 5 and the point 8, and it thus increases the effective resistance of the spring to the motion of the follower as the buffing increases in force. Meanwhile, the follower 4 is held by its stops and affords the necessary resistance to the lever 6. In pulling, the yoke 3 draws the follower 4 forwardly, and the follower 5 is held by its stops. A like action takes place with reference to the shifting of the points of contact of the followers 4, 5 and levers 6, 7, for as the follower 4 advances, its point of contact with the lever 6, and the point of contact of the lever 7 with the follower 5 move inwardly, and the effective resistance of the spring 9 is increased as above stated.

The advantages of my invention will be appreciated by those skilled in the art. It is simple and effective, and takes up so little room that it can readily be applied to use in all cases where draft-riggings of the kind now commonly employed are applicable.

The invention may be modified in many ways, without departing from the definition thereof as stated in the claims, since

What I claim is:—

1. A draft-rigging having differential levers projecting downwardly beyond the line of the draw-bar and having spring mechanism.

2. A draft-rigging comprising followers, differential levers bearing against each other and bearing on the followers, and a spring interposed between them.

3. A draft-rigging comprising followers, a spring, and differential levers bearing against each other and on the followers at their forward and rear faces, and having their sole pivotal bearings at the said bearing faces.

4. A draft-rigging comprising followers, a spring, and differential levers bearing against each other and on the followers at their forward and rear faces, and projecting outwardly beyond the line of the draw-bar. 5. A draft-rigging having followers, differential levers bearing against each other, bearing also on the followers and projecting outwardly beyond the line of the draw-bar and having a spring. 10. A draft-rigging having differential levers slotted to permit passage of a yoke and extending outwardly beyond the yoke, a yoke passing through the levers, and spring mechanism. 15. A draft-rigging comprising followers, levers bearing against each other and having curved faces bearing on the followers, said parts and followers having toothed faces. 20. A draft-rigging having levers and a yoke, said levers being slotted to admit passage of the yoke and extending outwardly beyond the same, and spring-mechanism. 25. A draft-rigging comprising followers, differential levers bearing against each other and bearing on the followers, and a spring, said followers and levers being interfitted and having toothed meeting faces. 30. A draft-rigging having followers, differential levers bearing against each other, bearing also on the followers and projecting outwardly beyond the line of the draw-bar and having a spring mounted on a rod between the levers. 35. A draft-rigging having differential levers with corrugated bearing surfaces. 40. A draft rigging having differential levers and followers with corrugated bearing surfaces. 45. A draft rigging having differential levers and followers, the meeting surfaces of the levers with the followers being corrugated. 50. A draft rigging having a follower and a lever projecting downwardly from the follower, and spring mechanism actuated by the lever. 55. A draft-rigging having a yoke, a lever slotted to permit passage of the yoke and extending outwardly beyond the same, and spring-mechanism actuated by the lever. In testimony whereof, I have hereunto set my hand.

CLINTON A. TOWER.
